FLAMETIGHT SWITCH HOUSING

John W. Herrick, Syracuse, N. Y., assignor to
Crouse-Hinds Company, Syracuse, N. Y., a
corporation of New York

Application July 13, 1936, Serial No. 90,320

3 Claims. (Cl. 200—168)

This invention relates to explosion resisting or flame tight housings for electrical switches and the like. The housing is particularly adapted to enclose switches and circuit breakers of comparatively large current carrying capacity, and an object of the invention is an explosion resisting housing of minimum weight, but of sufficient strength to meet the requirements of a fitting of this type.

10 A further object of the invention is a fitting of the type referred to which is of such structure that it can be readily and conveniently installed, and the complete interior of the fitting exposed for manipulation of the heavy wiring and the installation of switches or circuit breakers.

15 A further object of the invention is the provision of means to prevent exposure of the interior of the device while the switch or circuit breaker is in on position.

20 Another object of the invention is the provision of means whereby the parts of the fitting, when assembled, are in flame tight relationship and such relationship does not depend upon the skill of the workman assembling the fitting.

25 The invention consists in the novel features and in the combinations and constructions hereinafter set forth and claimed.

30 In describing this invention, reference is had to the accompanying drawing in which like characters designate corresponding parts in all the views.

Figure 1 is a vertical, sectional view of the housing with one end section thereof partly in elevation.

35 Figure 2 is a side elevational view.

Figure 3 is a bottom plan view, partly in section.

The invention comprises generally, an explosion resisting switch housing including a pair of end sections, means for maintaining the end sections in spaced apart relationship and in axial alignment, the means connecting the end sections also serving as a switch or circuit breaker support. The invention further includes a tubular body section sleeveable over one of the end sections and having its ends coacting with the end section in flame tight relationship thereto, and means carried by one of the end sections and operable from the outside thereof to actuate the switch into on and off position. One or both of said end sections are provided with conduit receiving passages and with means operable to prevent removal of the tubular body section when the switch is in on position.

5 The housing is illustrated in Figures 1 and 2 as

being mounted in a vertical position. The upper and lower end sections 10, 11, are substantially cylindrical in form, and the upper end section is provided with a leg or boss 12 for the purpose of securing the housing to the wall, or a support 13. 5 The upper end section is further provided with a depending annular flange 14 having an outer cylindrical surface. The lower end section 11 is connected to the upper section and supported by a plurality of rod members 15. These rod members 15 also provide a convenient means of supporting the switches or circuit breakers 16, as will be hereinafter explained. The lower end section is formed, or provided, with an outwardly flaring flange 17 extending in a general direction toward 15 the upper end section 10. That is, the outer surface of the flange 17 is tapered outwardly and upwardly.

One of the end sections, such as the lower section 11, is provided with means operable from the outside thereof to actuate the switch into on and off positions. This means comprises a rock shaft 18 journaled in the bottom of the end section and to the outer end of which is secured an operating manual 19. The upper end is provided with a crank member 20 which operatively engages the movable handle 22 of the switch 16. The arrangement of this mechanism is such that when the manual 19 is oscillated, as indicated by the arrow Figure 3, the handle 22 of the switch 16 is moved or oscillated about its pivot to actuate the switch into on or off position. Preferably four rods 15 are employed to connect the end sections 10, 11, and cross members 24 are attached to two or more of the rod members and provide a support to 35 which the switches 16 are attached.

The housing is completed by a tubular body section 23, one end of which is provided with a bore to form a tight sliding fit with the flange 14 of the end section 10, and the other end is provided with a tapered bore complementary to the outer surface of the flange 17. The flanges 14, 17, are of such relative dimensions that the tubular body section 23 may be sleeved upwardly over the flange 17, the upper end of the body encircling 45 the flange 14. It will be observed that when the tubular body section 23 is moved upwardly until the bore of the lower end thereof coacts with the flange 17, a flame tight joint is established between the ends of the tubular body and the 50 flanges 14, 17 of the end sections 10, 11.

Means is provided for maintaining the tubular body section in assembled position as shown in Figures 1 and 2 and with the lower end pressed firmly against the flange 17. This means com- 55

prises two or more collar screws 25 threading into the lower end section, with the collars overlapping the lower edge of the tubular casing 23. In the event the tubular body section 23 should become seized on the end sections, the upper end section 10 is provided with one or more bosses 26 threaded to receive the screws 27. The bosses 26 and screws 27 are so arranged relative to the tubular casing 23 that the ends of the screws 27 contact the upper edge of the casing, and as the screws 27 are tightened the casing is moved downwardly toward the bottom section 11.

It will be observed that the structure thus far described makes the housing of minimum weight and of maximum strength. Also, the flanges 14, 17 and the bores in the ends of the tubular casing 23 require a simple machining operation inasmuch as all these surfaces are cylindrical, and it will be further observed that when the tubular casing 23 is sleeved downwardly, as indicated by dotted outline Figure 2, the entire interior of the housing is accessible permitting the switches 16 to be readily and conveniently installed and connected to the electrical conductors.

25 One or both of the end sections 10, 11, may be provided with conduit receiving passages as hubs 30. If the lower end section is connected to a conduit as 31, the supporting bracket 32 for the conduit will act as a stop or rest for the tubular casing 23 when in its lowered position.

30 The conduit line 31 may be provided with a conventional sealing fitting 33 in which sealing compound is introduced to seal off the conduit run from the interior of the fitting.

35 In order to prevent accidental or unintentional removal of the tubular body section 23 while the switches 16 are in on position, the lower end section 11 is provided with a sliding member 35, the outer end of which, when the member is in out position, overlaps the lower end of the tubular casing 23, as indicated in Figures 1 and 3. The inner end of the slide member 35 is cooperable with the rock shaft 18. The rock shaft 18 is provided with flattened sides 36, and the inner end of the slide member 35 is provided with a groove which is of such width as to permit the slide member 35 to be moved inwardly when the flattened sides 36 of the shaft 18 are arranged parallel with the sides of the slot 37 and member 35. 40 However, when the flattened sides 36 extend crosswise of the slot 37, the member 35 may not be retracted from its outer position. The member 35 is slidably mounted on the lower side of end section 10 by means of screws 38 which may be of the break-neck type to prevent removal of the slide 45 member 35 after the fitting is put in service.

50 If the conduit bracket 32 is located relatively, as shown in Figure 2, the upper end of the body section 23 covers the switch actuating mechanism 55 when the body section is removed, as shown by dotted outline in Figure 2. This prevents accidental operation of the switches 16 while the interior of the housing is exposed.

What I claim is:

1. An explosion resisting switch housing comprising an end section provided with a depending annular flange, a second end section, means connecting the second end section to said first section in axial alignment therewith, said connecting means also comprising a switch support, said second end section being provided with a tapered peripheral surface, a tubular casing sleeveable over said second end section and being provided at one end with a bore to receive the flange of said first section, and at the other end with a tapered bore complementary to the periphery of said second end section, and means operable to effect axial movement of the casing relative to the end sections to bring the end portions of the casing into engagement with said end sections. 10

2. An explosion resisting switch housing comprising an end section having an outer cylindrical surface, a second end section supported from said first section in spaced apart relationship thereto and in axial alignment therewith, said second end section being provided with an outer cylindrical surface tapering outwardly toward said first section, a tubular casing provided at one end with a bore closely fitting the cylindrical surface of said first end section and provided at its opposite end with a tapered bore complementary to the outer tapered surface of said second end section, means associated with said second end section and operable to move said tubular casing axially toward said first section until the end bores of said casing engage the outer surfaces of said end sections, and means operable to move said casing toward said second end section to facilitate removal of the casing from said end sections. 20

3. An explosion resisting switch housing comprising an end section provided with means for attaching the same to a support and being also provided with a depending cylindrical flange, a second end section, supporting members located within the flange of the first section and arranged to support said second section in spaced apart relationship to the first section and in axial alignment therewith, said second section being provided with an upwardly extending annular flange provided with an outwardly tapering surface, a tubular body section provided at one end with a straight bore to receive the flange of said first section and provided at its opposite end with a tapering bore complementary to the tapered surface of said second end section, said connecting members also serving as a switch support, means carried by the second end section and operable from the outside thereof to actuate the switch into on and off positions, said tubular casing being sleeveable over the second end section toward said first section, and means for detachably securing said tubular body into engagement with said end sections. 40
